(57) CLAIM

We claim the ornamental design for oven range, as shown and described.

DESCRIPTION

FIG. 1 is a Perspective view of oven range showing the new design:

FIG. 2 is a Front Elevation View thereof;

FIG. 3 is a Rear Elevation View thereof;

FIG. 4 is a Left-side Elevation View thereof;

FIG. 5 is a Right-side Elevation View thereof;

FIG. 6 is a Top Plan View thereof; and,

FIG. 7 is a Bottom Plan View thereof.

The broken line showing of an oven is for illustrative purposes only and forms no part of the claimed design.
